CHARLES H. ROBINSON, OF GREENWICH, NEW YORK.

Letters Patent No. 92,102, dated June 29, 1869.

IMPROVEMENT IN COMBINED DRAWER-PULL AND LABEL.

The Schedule referred to in these Letters Patent and making part of the same.

To all whom it may concern:

Be it known that I, CHARLES H. ROBINSON, of Greenwich, in the county of Washington, and in the State of New York, have invented certain new and useful Improvements in Combined Drawer-Pull and Label; and do hereby declare that the following is a full, clear, and exact description thereof, reference being had to the accompanying drawings, and to the letters of reference marked thereon, making a part of this specification.

The nature of my invention consists in the combination of a drawer-pull and label, and in the arrangement of the devices hereafter set forth and explained.

Figure 1 is a front view of my invention.

Figure 2 is a rear view of the same.

Figure 3 is a section view of the same.

Letter A represents a curved metal plate, in the face of which there is cut an opening, through which the label or tablet B is shown. The ends of this plate are turned at right angles to the face, and are made to slant towards the top, as seen in fig. 3, so that there will be room enough between the bottom edge and drawer to insert the fingers, so that it can be used as a drawer-pull or knob.

Upon the back of the plate A there is a number of small hooks or catches D, which form a bed in which the label B rests. This label may be made of glass, metal, or any suitable substance, and can be

raised up above the hooks and removed without taking off the plate A.

In case the label should be made of glass, the plate C is placed back of it, so as to serve as a guard. This plate is intended to be entirely separate from the plate A, and is secured in place by the screws which fasten the front plate. There is a slot cut in the lower edge of this guard, extending upward, so that the fingers can grasp hold of the label both in front and behind, so that it can be raised out of the hooks, in order to be removed.

When the label or tablet is formed of metal, or some substance not easily broken, this guard can be dispensed with.

Having thus described my invention,

What I claim, and desire to secure by Letters Patent, is—

1. The slotted plate C, when used as a protection for the label, substantially as set forth and described.
2. The plates A and C, and label B, when combined so as to form a combined drawer-pull and label, substantially as specified.

In testimony that I claim the foregoing, I have hereunto set my hand, this 12th day of May, 1869.

CHARLES H. ROBINSON.
